UNITED STATES PATENT OFFICE

AXEL FOLKE CARLSON, OF CAMBRIDGE, MASSACHUSETTS, ASSIGNOR TO REECE SHOE MACHINERY COMPANY, OF BOSTON, MASSACHUSETTS, A CORPORATION OF MAINE

SHOE SEWING MACHINE

Application filed March 31, 1928. Serial No. 266,421.

This invention relates to shoe sewing machines, and more especially to the control or regulation of the thread and the application and variation of tension thereon. Machines of the class to which the present invention is applied are exemplified by the Reece welt-and-turn machine which is a power driven stitching machine in which the upper of a boot or shoe is stitched to the lip of the insole, and frequently to a welt strip. Instances of such machines are those illustrated in patent of Zaleski and Schoenky No. 1,288,366 of December 17, 1918, and subsequent patents, such as the patents of J. R. Oliver 1,605,060 of November 2, 1926 and Patent 1,688,938 of October 23, 1928, wherein chain stitches are applied by the use of a curved hooked needle and cooperating instruments. The novel features hereof however are applicable to other types of shoe or leather stitching machines.

The general object of the present invention is to improve the handling of the thread in shoe sewing machines, and especially to improve the operation and efficiency of the thread tension control mechanism which cooperates with the take-up and other instruments taking part in the formation of stitches. A specific object is to provide improved automatic means for causing a certain change in tension upon the thread at certain points in the stitch cycle, the tension or resistance on the thread supply being heavy at certain periods, including the taking up and setting of the stitch, and light at other periods.

Other and further objects and advantages of the present invention will be explained in the hereinafter following description of an illustrative embodiment thereof or will be apparent to those skilled in the subject.

To the attainment of the recited objects and advantages the present invention consists in the novel shoe sewing machine, and thread tension mechanism, and the novel features of combination, arrangement and structure herein illustrated or described.

In the accompanying drawings Fig. 1 is a right elevation of a sufficient part of a Reece welt sewing machine to illustrate in connec-

tion with the other figures the principles of the present invention.

Fig. 2 is a top plan view of the characteristic portions of the mechanism.

Fig. 3 is a vertical section, looking from the front, taken substantially on the line 3—3 of Fig. 2.

Fig. 4 is a face view of the thread wheel shown in the other figures.

Fig. 5 is a vertical section, looking from the right, taken substantially on the line 5—5 of Fig. 3.

Similar reference numbers are applied to corresponding parts in the several figures of the drawings.

Referring to Fig. 1 there is indicated a shoe in sewing position. Surrounding the last *l* is the insole *s* with its outturned lip *s'*, the shoe upper *u*, and the welt strip *w* being fed and attached by thread *t* to the upper and insole lip.

The machine may comprise the usual tall post *9* at the upper end of which is a suitable head or frame including fore-and-aft frame walls *10* and *11*, being the two usual frame walls giving support to the mechanism of this invention. The stitching shaft *13* is shown as turning in the frame walls in conjunction with other usual bearings.

The thread *t*, which may come from a wax pot at the rear passes first to the thread wheel *14* around which the thread travels subject to the restraining action of the tension control or device to be described. The thread, from the tension, passes to a take-up lever *15* and thence to the usual looper *16* operated to apply a loop of the wax thread to the barbed point of the needle *17*, successive stitches thus being formed, while, between stitches, the work is fed forwardly by the usual reciprocating feed point or device *18*. The shoe is shown held to position against a work rest *19*, intermittently yieldable, and it bears also against a welt guide *20* supported on a carrier *21*, which also may be intermittently yieldable. Above the welt guide and carrier is shown a series of mechanical parts for controlling the movements thereof during stitching, but these will not be described.

herein, as they form no part of the present invention.

Coming now to the tension mechanism, the preferred operation of the present invention is that two separate resistances to the thread wheel or thread are provided, one quite heavy and amounting to a locking action, the other much lighter, these normally being both in effect, but the heavy resistance or friction being released or removed intermittently, that is at the proper point in each stitch cycle, while the light tension remains in effect throughout the stitching; and the tension preferably being operated so that at the end of the stitching, not only the heavy tension but the light tension, is removed, thus leaving the thread free to be drawn from the supply with the removal of the work from the machine.

20 The thread wheel 14 is shown as having a hub 25 turning on an axle 26, and the hub carrying also a friction drum 27 through which resistance or friction can be applied to the thread wheel and thread.

22 Bearing on the tension drum 27 are shown two separate friction members or shoes, a rear friction shoe 30, herein employed for the light tension, and a front shoe 31, herein employed for the high or heavy tension; each friction shoe having a friction facing 32. For convenience both of the friction shoes may be fulcrumed on the same stud 33 shown directly beneath the axle 26. The stud 33 is supported on a fixed bracket 34, as shown in Fig. 3, this being a portion of a more extended bracket, having a portion 35 which extends around and above the axle 26 and an upper portion 36 forming a bearing for a part 51 to be described, and a portion 37 which is attached rigidly to the frame wall 11, as seen in Fig. 2.

45 The rear or light tension shoe 30 is shown as applied by a spring 38, this spring surrounding an interior rod 39 having its rear end threaded to carry an adjusting nut 40 and a lock nut 41, by which the spring pressure can be exactly adjusted to the light tension desired. The forward end of the rod 39 is supported by a horizontal stud 42, the rod having an eye surrounding the stud. The stud 41 is mounted fixedly in a boss 43 formed on the fixed bracket member 37. Thereby the forward end of the tension rod 39 is held stationary, subject to rocking motion, while the rear end carries the adjusting nuts 40 and 41.

50 The heavy tension is applied by a front spring 45 surrounding a rod 46 carrying at its free or forward end a nut 47 and lock nut 48, the rear or inner end of the rod 46 having an eye surrounding the fixed stud 42. The nuts 47 and 48 will be adjusted to give the desired powerful resistance and heavy tension.

60 65 The front or heavy tension shoe 31 may be

relaxed or released intermittently by means of a rocker or finger 50, which is shown mounted on a rock shaft 51 supported in the bracket portion 36. The finger is at the left end of the rock shaft and at its right end it carries a hub 52 formed into a rock arm 53 carrying a cam roll 54. These elements shown in full lines in Figs. 2 and 3 are indicated in dotted lines in Fig. 1 where the rock arm 53 is shown pressed by a spring 55 so that the cam roll 54 bears against the periphery of a cam 56 mounted on the stitching shaft 13. The cam is shown as having an eccentric portion 57 allowing the cam roll to move forwardly and thus apply the heavy tension. In the position shown in Fig. 1 the heavy tension is in effect. After a further rotation the eccentric cam portion 58 will come into effect to lift the cam roll rearwardly and thus swing the rock finger 50 to press forwardly the shoe 31 and thus release the heavy tension.

such matters except so far as set forth in the appended claims.

What is claimed is:

1. In a power driven shoe sewing machine, in combination with the needle and take up and cooperating stitch forming and work feeding means, a thread control means comprising a thread wheel between the thread supply and take up, and a brake drum turning with the thread wheel, a first peripheral brake shoe at one side of the drum for applying intermittent resistance to the thread wheel, a second peripheral brake shoe at the other side of the drum for applying continuous resistance thereto, said brake shoes being both pivoted at the same side of the brake drum and each having an extension at the opposite side of the drum, with spring means normally acting on said extensions to apply both said shoes to the drum, and timed means acting to remove the first brake shoe at predetermined points in each stitch cycle.

2. In a power driven shoe sewing machine, in combination with the needle and take up and cooperating stitch forming and work feeding means, a thread control means comprising a thread wheel between the supply and take up, and a brake drum annexed thereto, a first brake shoe at one side of the drum and a second brake shoe at the opposite side, said brake shoes being pivoted on a common axis, and having extensions opposite such axis, pressure springs normally acting on said extensions to apply the brake shoes to the drum, adjusters therefor, and means operating in each stitch cycle to remove the pressure of the first brake shoe and compress its spring.

In testimony whereof, I have affixed my signature hereto.

AXEL F. CARLSON.
